UNITED STATES PATENT OFFICE.

SIDNEY MARION TEPPER, OF CLEVELAND, OHIO.

SAW.

Application filed February 2, 1926. Serial No. 85,549.

My present invention has reference to what I will term a combination handsaw.

My object is to provide in a single implement, a saw, a square, a gage, a rule, and a bevel, so that the separate use of all of these tools will be at the command of the owner of the device, so that the inconvenience of carrying a plurality of tools and the loss of time required in finding or removing such tools from the workman's box or bench will be effectively obviated.

To the attainment of the above broadly stated objects the improvement further resides in certain novel features of construction, combination, and operative association of parts, a satisfactory embodiment of which is illustrated by the accompanying drawings:

In the drawings:

20 Fig. 1 is a side elevation of a tool in accordance with this invention.

Fig. 2 is an enlarged elevation showing the gage set to scribe marks on timbers or the like at 60 degree angles,

25 Fig. 3 is a view showing the manner in which the tool is employed for scribing right-angled lines on timbers or the like,

Fig. 4 is a similar view showing the manner in which the device is employed for scribing a board or timber to be cut into desired 30 lengths,

Fig. 5 is a similar view showing the manner in which the tool is employed as a measuring device,

35 Fig. 6 is a sectional view on the line 6—6 of Fig. 5,

Fig. 7 is a side elevation of one of the elements constituting the combined square and bevel attachment,

40 Fig. 8 is a top plan view thereof,

Fig. 9 is a similar view of the companion member,

Fig. 10 is a perspective view of the set-screw, and

45 Fig. 11 is a similar view of the elements for pivotally associating the arms constituting the combined square and bevel attachment.

Essentially my improvement includes a 50 saw blade 1 having attached to one end thereof the usual handle 2. The bifurcated portion of the handle, at the inner edge thereof, is provided with the usual beveled lips 3 which afford a larger bearing surface for the portion of the handle that engages the saw blade. This is of the usual construction.

For distinction, the ends of the handle that merge into the lips are indicated by the numerals 4 and the nontoothed edge of the blade 1, indicated for distinction by the numeral 5, is arranged at a right angle with respect to the said handle end 4. Also the said edge 5 of the blade, from the ends 4 of the handle, has inscribed thereon a rule, divided into inches and into fractions of inches indicated by the numeral 6. Inward of the rule scale, but in a line with the graduations thereof, the blade 1 is provided with substantially rectangular openings 7. All of these openings are arranged in parallelism, and the outer walls provided by the openings, that is, the walls nearest the edge 5, are cut at opposite angles to the center thereof and are thus substantially V-shaped as indicated by the numeral 8.

The saw blade, at the beginning of the rule scale, and at a point adjacent to the juncture of the handle with the said blade, is provided with a transverse rounded opening 9.

Scribed on the saw blade from the axial center of the opening 9 there are on either or both faces other round openings 10 and degree marks 11 between the said openings. The degree marks provide the saw blade 35 with what may be termed a protractor scale.

In carrying out my invention I provided a combined square and bevel attachment that constitutes two members in the nature of flat bars or arms 12 and 13, respectively. Both 90 of these arms have their inner edges concaved longitudinally, as at 14, to receive therein the lips 3, when the members are pivotally associated with the saw blade which will now be described.

The member 12 has its inner face provided with a round opening in the nature of a socket 14' that is adapted to receive therein a boss 15 on the inner face and at the end of the member 13. The member 12 has a 100 square opening 16 which opens into the opening 14', the outer face of the said member 12 having a round depression 17 that surrounds the said opening 16, while the boss 15 is formed with a squared opening 18 which registers with the opening 14' in the member 12. The outer face of the member 13 is formed with an annular depression 19 that surrounds the said squared opening 18. Passed through the squared openings there is the squared shank 20 of a bolt member, the head 21 of the said bolt member being 110

received in the depression 17. The threaded end 21 of the bolt member is reduced and is received in a threaded socket of a rounded nut 22 which is received in the depression 19. 5 The nut 22 has its outer face kerfed, as at 23, whereby the said nut may be turned by a screw-driver or the like.

As most clearly disclosed in Fig. 6 of the drawings, the rounded boss 15 passes through 10 the opening 9 in the saw blade 1, and in this manner both of the arms are effectively secured together and pivotally supported on the saw blade. The arm 13, adjacent to the non-pivoted end thereof, has a rounded opening 27 therethrough, and the member 12 has a threaded opening 28 which registers with the said rounded opening. There is passed through the non-threaded opening the non-threaded shank 24 of a screw-bolt 25, the 15 threaded shank 26 of the said bolt being screwed through the threaded opening in the member 12. This, however, does not occur until the openings 27 and 28 in the members 13 and 12 are brought to register with 20 each other and arranged opposite any of the arcuately arranged openings 10 in the saw blade. When the bolt 25 locks the arms on the saw blade, against the shoulders 4 of the handle 2, the outer edges of the arms 25 providing the combined square and bevel are disposed and locked rightangularly with respect to the straight edge 5 of the saw blade and when so arranged the arms and the saw blade provide a square. When the 30 saw blade is arranged against one face of a timber, as illustrated by Fig. 5, and one of the arms is brought against the edge of the timber, the rule scale on the saw blade permits of the accurate measurements being 35 made on said timber. The saw is held in the same position when the outer straight edge of the blade thereof is employed for scribing purposes, as illustrated in Fig. 3. When in this position the saw may be employed, as a means for scribing mark lines 40 on a timber, as disclosed by Fig. 4. In this instance, the carpenter's pencil is inserted through the desired opening 7 in the blade and the sharpened edge thereof is brought 45 into the V-shaped notch at the end of the said opening. The saw is simply drawn along the edge of the timber. When employed as a bevel, the arms are swung on 50 the saw blade to arrange the same in the 55 position illustrated in Fig. 2, when a cut

or a scribe mark of 60 degrees is required. Of course, by bringing the blades opposite any other of the degree marks 11 and passing the binding element through the openings in the arms and through the opening 10 in the blade, the said arms will be retained at desired angles so that timbers may be scribed for making proper angle cuts. 60

My improvement is of an extremely simple construction and may be cheaply manufactured and marketed. The improvement, as previously stated, embodies in a single article a great number of tools which are necessary in the work of carpenters or joiners, and it is believed that its many advantages will be readily understood and appreciated by those skilled in the art to which this invention relates when the foregoing description has been carefully read in connection with the accompanying drawings. 75

Having described the invention, I claim:—

A tool of the class described, including a saw blade and a handle therefor, said handle having its inner edge arranged rightangularly with respect to the non-toothed edge of the saw blade, said blade at its said non-toothed edge being inscribed with inch marks and fractions thereof, and being provided in a line with such marks with transverse openings, a combined square and bevel attachment pivotally secured adjacent to the straight edge of the saw blade at the junction of the handle therewith, said attachment comprising two flat arms, one of which having a boss that passes through the saw blade and that is received in the second arm, both of said arms at the pivotal connection thereof having square openings therethrough, each of which being surrounded by a recess, a headed bolt having a squared shank passing through the squared openings and the head thereof received in one of the said recesses, said shank having its outer end formed with a threaded extension, a rounded nut received in the depression or recess of the second arm and screwed on the threaded end of the bolt, and a binding bolt passing through the second ends of the arms and the openings in the saw blade for holding the arms against the handle or for holding the said arms at different angle positions on the saw blade. 90 95 100 105

In testimony whereof I affix my signature.

SIDNEY MARION TEPPER.
